CLAIM

The ornamental design for a hood ornament, as shown and described.

DESCRIPTION

FIG. 1 is a perspective view of a hood ornament showing our new design;

FIG. 2 is a reduced front view thereof;

FIG. 3 is a reduced right side view thereof, the opposite side view being a mirror image of that shown;

FIG. 4 is a reduced rear view thereof;

FIG. 5 is a reduced top view thereof; and,

FIG. 6 is a reduced bottom view thereof.

The mounting hardware shown in broken line is for illustrative purposes only and forms no part of the claimed design.
